UNITED STATES PATENT OFFICE.

ANDREAS BITTER AND ERNST WEISSBERG, OF CASSEL, GERMANY.

HIGH-TENSION CONNECTING-INSULATOR.

1,058,143.

Specification of Letters Patent.

Patented Apr. 8, 1913.

Application filed September 4, 1912. Serial No. 718,578.

To all whom it may concern:

Be it known that we, ANDREAS BITTER and ERNST WEISSBERG, both engineers and subjects of the German Emperor, residing at 5 Cassel, Germany, have invented a new and useful High-Tension Connecting-Insulator; and we do hereby declare the following to be a full, clear, and exact description of the same.

10 This invention refers to a safety fuse for electric apparatus and of the type employing oil, such electric apparatus being for example distributing transformers and oil switches.

15 According to the present invention the cartridge with the fuse wire is removably arranged in the connecting or leading-in insulator or terminal of the apparatus, and its fuse chamber is connected at its inner 20 end with the oil space of the apparatus. The fuse chamber will thus be elastically sealed because the connecting insulator can be arranged in the open like the Delta petticoats and consequently the whole arrangement can be used for very high tensions.

The accompanying drawing shows one form of construction.

Figure 1 shows in sectional elevation a complete insulator with built-in safety fuse; 30 Fig. 2 shows a longitudinal and a cross section of the removable cartridge.

The cartridge consists of a cylindrical tube *b* made of strong insulating material and coated with fireproof material *c*. The tube is provided at the top and bottom with metal stoppers or plugs *d* and *e*, in which the fuse wire *a* is soldered. The lower stopper *e* is perforated. A metal rod *s* is screwed into the upper stopper *d* through which the 40 current is supplied and by means of which the cartridge can be introduced into or removed from the insulator *f*. This insulator is arranged in the lid *h* of the case which contains oil and it carries at top and bottom metal caps *i* and *k* firmly cemented in place, to which can be connected the lead and return wires for the current. A screw thread or bayonet joint is provided on the 45 upper cap *i* so that the inner chamber of the insulator can be shut off by means of the hood *l* from the atmospheric air, suitable packing material being employed. The chamber in the insulator communicates through an opening in the lower cap *k* with the oil chamber of the apparatus, the fuse

wire *a* being covered to above 1/3rd of its length with oil.

In order to prevent metal particles falling out into the case as well as a too rapid expulsion of the oil from the fuse chamber 60 the opening *o* can be covered over by means of a sieve or strainer.

The safety device works as follows:— Upon any short-circuiting taking place the portion of the fuse wire *a* situated above the 65 oil will be melted and evaporated, and owing to the resulting pressure occasioned thereby a portion of the oil will be expelled through the opening *o*. A further portion of the fuse wire will thus be exposed and 70 also immediately melted. The hot metal vapors will at the same time come into contact with the oil, are condensed, the pressure disappears and the pursuing oil will cover the end of the fuse wire so that on the next 75 passage of the alternating current through the point of zero value the arc will be extinguished.

The safety is considerably increased owing to the fact that the arc is completely enclosed by solid insulating material and any bursting of the insulator appears impossible inasmuch as it is stiffened at both ends as well as in the middle by metal rings; the slight pressure arising can only occur in the 85 cartridge which is made of strong material.

In order, in accordance with the present invention, to protect the thin fuse wire from being destroyed by ozone, a concentric metal sheet jacketing *m* is provided which is connected to the current supply at *i*.

Having thus described our invention, what we claim as such and desire to secure by Letters Patent is:—

1. A safety fuse for electric apparatus containing oil, comprising a connecting insulator, a cartridge with the fuse wire arranged in said connecting insulator and a fuse chamber shut off from the atmosphere and communicating at its inner end with the oil contained in said apparatus, so that a portion of the fuse wire is covered with oil, the oil thus forming an elastic sealing of the fuse chamber.

2. A safety fuse for electric apparatus containing oil, comprising a connecting insulator, a cartridge with the fuse wire arranged in said connecting insulator and a fuse chamber shut off from the atmosphere and communicating at its inner end with the

oil contained in said apparatus, so that a portion of the fuse wire is covered with oil, the oil thus forming an elastic sealing of the fuse chamber, and a concentric metal cylinder connected to the current supply and arranged in said insulator, for protecting said fuse wire from being destroyed by ozone.

In testimony whereof, we have signed our

names to this specification in the presence of two subscribing witnesses.
